UNITED STATES PATENT OFFICE.

OSCAR M. ARNOLD, OF NEW YORK, N. Y.

DESIGN FOR A PARASOL.

47,179.

Specification for Design.

Patented Apr. 6, 1915.

Application filed January 6, 1915. Serial No. 875. Term of patent 3½ years.

To all whom it may concern:

Be it known that I, OSCAR M. ARNOLD, a citizen of the United States, residing in the city of New York, borough of Manhattan, in the county and State of New York, have invented a new, original, and ornamental Design for a Parasol, of which the following is a specification, reference being had to the accompanying drawing, forming a part thereof.

The figure is a side elevation of a parasol showing my new design.

I claim:

The ornamental design for a parasol as shown.

OSCAR M. ARNOLD.

Witnesses:

ROBERT ROY, Jr.,
JOHN H. BRUTT.
